FLARE

Harold S. Eroe, Wharton, N. J., assignor to the Government of the United States of America, as represented by the Secretary of War and his successors in office

Application May 25, 1938, Serial No. 209,965

3 Claims. (Cl. 102—24)

(Granted under the act of March 3, 1883, as amended April 30, 1928; 370 O. G. 757)

The invention described herein may be manufactured and used by or for the Government for governmental purposes, without the payment to me of any royalty thereon.

5 The subject of this invention is a flare.

Ground flares for illuminating the landing field of an airport are employed in large numbers and are individually ignited. In order to obtain effective illumination of the field the flares should be 10 positioned some distance above the ground, for example fifteen feet.

The purpose of this invention is to provide a flare in which the ignition mechanism is so arranged that it may be readily operated by a person 15 son on the ground. By virtue of this arrangement one person may ignite a large number of flares in a short space of time.

To these and other ends, the invention consists in the construction, arrangement and combination of elements described hereinafter and pointed out in the claims forming a part of this specification.

A practical embodiment of the invention is illustrated in the accompanying drawing, 25 wherein,

Fig. 1 is a view in side elevation of the improved flare carried on a mast and prepared to be ignited;

Fig. 2 is a longitudinal sectional view of the 30 flare with the shipping cover in place;

Fig. 3 is a transverse sectional view through the cap and the ignition mechanism taken on the line 3—3 of Fig. 4;

Fig. 4 is a sectional view on the line 4—4 of 35 Fig. 3;

Fig. 5 is a sectional view on the line 5—5 of Fig. 4.

Referring to the drawing by characters of reference the flare comprises a tubular casing 5 where- 40 by it is mounted on a mast A and a tubular casing 6 which is attached to the casing 5 and contains a charge 7 of an illuminating composition and the usual first charge 8.

A metal cap 9 mounted on the end of the casing 45 6 and attached thereto by means of shellac varnish is formed with a diametrically extending arched portion 10 which constitutes a housing for containing the igniting mechanism. A thimble 11 containing an annular compressed primer charge 12 is held in the arched portion by crimping the bases thereof as at 13—13 and it is maintained in one end of the arched portion by crimping the sides thereof as at 14—14.

A pull wire 15 having a coiled inner end 16 50 coated with a friction composition 28 is threaded

through the annular primer 12 then through an aperture 17 in the base of the thimble, and finally through an aperture 18 in the sloping end wall 19 of the arched portion. A bend 20 is then formed in the wire and is disposed in the space between 5 the thimble and the sloping end wall. This bend provides resistance to accidental movement of the wire during storage, handling and preparation of the flare for use. The outer end of the wire is formed into a loop 21 to which a long cord 22 is 10 attached. The aperture 18 is sealed as at 23 with a suitable material such as paint. The cap 9 is provided with vent holes 24—24 which are normally closed by rupturable waterproof sheets 25 affixed to the cap.

15 A shipping cover 26 fitting over the metal cap 9 and confining the coiled wire 15 and cord 22 is retained in a conventional manner by means of adhesive tape 27. This cover is removed when the flare is placed on the mast in readiness for 20 use, and the cord 22 is positioned to be conveniently seized by an operator. The igniting mechanism is functioned by merely pulling the cord.

I claim:

1. In a flare, a casing, a cap on one end of the 25 casing, said cap formed with a diametrically extending arched portion having a sloping end with an aperture, a thimble held in one end of the arched portion by crimping the bases and sides of the arched portion, a primer carried by the 30 thimble, a pull wire passing through the primer and the aperture in the sloping end of the arched portion, said wire having a bent portion disposed between the thimble and the sloping end of the arched portion.

35 2. In a flare, a casing, a cap on one side of the casing, said cap formed with a diametrically extending arched portion having a sloping end with an aperture, a thimble held in one end of the arched portion, a primer carried by the 40 thimble, a pull wire passing through the primer and the aperture in the sloping end of the arched portion, said wire having a bent portion disposed between the thimble and the sloping end of the arched portion.

45 3. In a flare, a casing, a cap on one end of the casing, said cap provided with a raised portion forming a housing, a primer carried within the raised portion and a pull wire passing through the primer and the cap and movable through the cap in igniting the primer, the inner portion of the said pull wire being coated with a friction composition.

HAROLD S. EROE. 55
